UNITED STATES PATENT OFFICE

2,503,408

GRADE GAUGE

George R. Phillips, Sacramento, Calif.

Application November 9, 1945, Serial No. 627,715

2 Claims. (Cl. 33—185)

1

This invention relates to grade gauges and has for its main object the provision of means for enabling the operator on a grader to accurately grade the ground to the desired level without stopping the grader to read figures or to take measurements.

Another object of the invention is the provision of a system or combination, including stakes driven into the ground for indicating to the operator on a grader exactly where the cutting edge of the grader blade is with respect to the desired finished level of the grade and which combination is so designed that if any one stake should accidentally be knocked over or dislodged by the grader blade, the operator may readily replace it with its original accuracy and without requiring any calculation.

Heretofore in grading roads or in grading fields or plots of ground for any special purpose such as for buildings or for airplane landings, football, baseball, etc., it has been the custom to first roughly grade the ground to about the desired level and then stakes are driven along the road sides or in rows at spaced intervals in the field, which stakes are marked to indicate the number of feet or inches to be taken away or to be filled at the points where the stakes are driven. Such marks may read "+12" or "-12" or "cut 12" or "fill 12," indicating that in order to produce the desired grade level at that point twelve inches must be cut or filled as the case may be. Obviously the result is more or less a matter of guesswork on the part of the operator who is driving the bulldozer, grader or scraper that is being used to do the job. The figures or marks used are ordinarily hard to read and if the stakes are knocked over, they may be obliterated or rendered illegible.

With the present invention the operator on the grader, scraper, carryall, or whatever piece of equipment is being used for the job, can readily see exactly where the cutting edge of the cutting blade is at all times relative to the desired finished level, either at night (using conventional lights) or in the daylight, thus enabling him to make the correct cut or fill, irrespective of how many times it may take to make the proper cut or fill. Should any of the stakes be knocked over they can readily be replaced by any inexperienced person with the accuracy of the original placement and there are no figures to be defaced.

In the drawings, Fig. 1 is a diagrammatic side elevational view of a grader of the bulldozer type having a grader gauge thereon and indicating stakes are shown for illustrating the invention.

2

Fig. 2 is a front elevational view of the device of Fig. 1.

Fig. 3 is an enlarged front elevational view of one of the grader gauges indicated in Fig. 2, the end of the grader blade being indicated in section.

Fig. 4 is a plan view of the grader gauge of Fig. 3.

Fig. 5 is a fragmentary perspective view of the hinge pin for the grader gauge, part of the base plate being in section.

Fig. 6 is a fragmentary perspective view of part of the grader gauge that is adapted to be pivoted on the hinge pin, a portion of the said part being in section.

In detail, referring to Figs. 1, 2, after the preliminary grading of the ground is accomplished there are usually depressions 1 in the surface and elevations 2 that are below and above the desired level indicated by the dot-dash line 3.

In carrying out the present invention stakes 4 are driven into the ground in the usual manner, but instead of these stakes bearing the conventional numbers designating the amount to fill or to cut they each have a mask 5 painted or otherwise affixed thereto. The stake is driven into the ground until the mask 5 is at a predetermined distance above the desired finished level 3. Thus in leveling a field or road anyone looking down a row of stakes will readily see that the marks 5 are all in regular alignment. If any stake is driven too deeply or not deeply enough, that fact will be readily apparent because the mask 5 will clearly be higher or lower than the marks on the other stakes in the row. Thus should any stake be inadvertently knocked over practically any inexperienced operator can replace it merely by seeing that the mask 5 is substantially aligned in a vertical plane with the marks 5 on the other stakes beyond it.

For the purpose of description, it will be assumed that the distance between the marks 5 on the stakes and the plane or level 3 is two feet or twenty-four inches. If the lower cutting edge 6 of the grader blade 7 is at the level 3 and is functioning to either cut the earth or to spread the previously cut earth 8 that may pile up in the blade or ahead of it, the fact is clear that the surface 9 over which the blade has passed will be exactly at the desired level. Several cuts and fills may be required to produce the finished desired level.

In order that the operator may know exactly when the cutting edge 6 of the blade has reached the finished level, as above described, a grade

gauges 10 are provided at the opposite ends of the grader blade 7 which gauges, in the above described example, are at a level twenty-four inches above the cutting edge 6 of the blade. Thus when the gauges pass the stakes at the level of marks 5 and the grader blade is cutting or spreading dirt, there is no question but that the level 3 has been reached and no more cutting or filling should be done.

The grader blade in the drawings is shown on the conventional blade elevating or lowering arms 11 of an ordinary tractor 12, such blade, arms and tractor being commonly termed a bulldozer. However, in so far as this invention is concerned, the particular implement may be a scraper of the carryall type or any other scraper using a scraper blade and arranged to fill as well as to cut. The mere provision of a blade adapted to push the dirt ahead of the same is satisfactory in most instances inasmuch as the heavy excavating or filling has ordinarily been accomplished and there is sufficient dirt in the elevated areas to fill the depressions.

The grade gauges themselves may comprise a base member 15 (Figs. 3, 4) adapted to be secured in any suitable manner, such as welding 16, bolting, brazing, etc. to the scraper blade or to any portion of the blade assembly at the ends thereof that may move with the blade. For example, in bulldozers and carryall scrapers the blade usually includes rigid end plates 17 at the ends of the blades to which the base member 15 may be secured. Otherwise the said member may be secured directly to the blade. The important thing is that the said member be secured rigidly in some manner or other to the blade for up and down movement as a unit with said blade and that said base member be a predetermined height above the level of the lower cutting edge of the blade.

Member 15 may have a vertical hinge pin 18 secured thereto and projecting from the side of the member facing outwardly of the adjacent end of the cutting blade.

A bracket 19 is pivotally secured to the hinge pin 18 by loops 20 encircling the pin which loops may be enlarged at one side as at 21 (Figs. 4, 6) for abutting the member 15 when the bracket 19 extends at right angles to member 15 or in a direction at right angles to the longitudinal axis of the bulldozer or scraper. This enlargement 21 is at the leading side of the hinge pin relative to the direction of travel of the scraper and, therefore, the bracket 19 may swing rearwardly if it strikes some object during forward movement of the scraper but it will not swing in the opposite direction or forwardly past the enlargement. A coil spring 22 (Fig. 4) secured to the member 15 and bracket 19 yieldably holds the bracket in its outwardly extending position and will return it to said position should it swing rearwardly.

The bracket 19 is formed with a vertically elongated head 23 (Fig. 3) that is formed with a vertical row of spaced holes 24 therein.

Removably secured to head 23 by a bolt 25 and a pin 26 is a support 27. This support 27 is formed with an opening for bolt 25. When pin 26 is in one of the holes 24 one of the openings 24 thereabove will be in register with the bolt opening in the support 27. Thus upon insertion of said bolt and tightening of the nut on the same, the support will be rigidly held on the bracket against any tendency to pivot in any direction. The use of the pin 26 merely obviates the necessity for using two bolts. Upon

removing bolt 25 the support 27 may be moved up or down to a new position on head 23.

Support 27 carries a horizontal pivot 28. The axis of pivot 28 is parallel with the longitudinal axis of the bulldozer or scraper and it pivotally supports a piece 29 that in turn has a horizontally extending flexible element 30 secured thereto at one of the ends of said element.

Piece 29 further includes a weight 31 that acts as a counterweight for blade 30 for holding element 30 horizontal at all times irrespective of the inclination of the grader blade and head 23 or support 27.

The element 30 is flexible and is practically the same as a hacksaw blade except for the absence of teeth. The element is positioned with its flat sides vertical thus no bending or sagging will take place vertically but the blade may, in a horizontal plane, yield in either direction. Preferably the rear side of said element 30 is painted white or a light tint so as to be visible in a dim light such as at night where the usual lights are used for night grading. Of course, both sides may be painted, but the important thing is that whatever side faces the driver of the bulldozer or scraper should be light to facilitate seeing it in a relatively dim light.

The marks 5 may be also light although the important thing is that they be in a color to clearly be seen by the driver in a dim light.

By reason of the structure as described above, it will be apparent that the driver can clearly tell when the grading has reached the desired level without reading the numbers and without making a guess as to whether or not the desired depth of cut or fill has been made.

It is to be understood that the detailed drawings and description are not intended to be restrictive of the invention but merely illustrative of a preferred form. For example, in many instances it would be possible to secure the element 30 directly to the grading blade or base member 15, but where the scraper is working in a cut or alongside a bank the blade 30 might be snapped off if it were not for the hinged bracket 19. Also were the grader or scraper always working on the level, the pivot 28 could be eliminated. For unusual use the structure disclosed or its equivalent in function is preferable.

I claim:

1. A grade gauge of the character described for securement to an upwardly extending end of a horizontally extending earth grading blade comprising a base member adapted for securement to said end, an elongated horizontally extending element secured at one end of its ends to said base member, said element being straight and flexible for yielding in a horizontal plane upon striking an object, means for securing said element to said member including a vertical pivot for swinging of said element horizontally, stop means to limit said swinging of said element in one direction to a predetermined position relative to said base member, spring means for yieldably holding said element in said predetermined position.

2. A grade gauge of the character described for securement to an upwardly extending end of a horizontally extending earth grading blade comprising a base member adapted for securement to said end, an elongated horizontally extending element secured at one end of its ends to said base member, said element being straight and flexible for yielding in a horizontal plane upon striking an object, and means for securing said element to said member at one of various

heights, a horizontal pivot supporting said element at its end adjacent said base member for vertical swinging of said element, and a counter-weight connected with said element at one side of said pivot for holding said element horizontal at all times.

GEORGE R. PHILLIPS.
